SPARK PLUG

Arch E. Hornback, Chicago, Ill., assignor of one-eighth to Chas. S. Deneen, three-sixteenths to Walter G. Davis, one-eighth to Gilbert Hardy, one-sixteenth to Emma Schumacher, and one-fourth to Albert Wilkinson, all of Chicago, Ill.

Application August 18, 1934, Serial No. 740,472

9 Claims. (Cl. 123—169)

This invention relates to spark plugs for internal combustion engines.

One of the objects of the invention is to provide a spark plug in which the porcelain parts are protected from the high temperatures existing in the combustion chamber of the cylinder. This object is partially accomplished by means of the construction of the center and intermediate electrodes whereby the plug end is baffled and the porcelain cores are almost completely enclosed and protected by heat resisting metal. The electrodes do not project beyond the end of the plug into the combustion chamber, and the end of the plug, as a whole, does not project to any appreciable extent beyond the water jacketed wall into which it is screwed. This arrangement also assists in preventing destruction of the cores.

Another advantage of the baffle construction to be described is the fact that in the event any part of the porcelain core should break, no particles of sufficient size to cause damage can pass into the cylinder.

Another advantage of my invention lies in the construction whereby a scavenging effect is produced on the spark areas or surfaces, thus keeping the plug efficient for spark output. The ignition of gas in the small gas chambers within the plug, having restricted communication with the combustion chamber of the cylinder, occurs more quickly than complete combustion does in the cylinder and thus there is produced a blast of gas from the plug through the narrow spaces between the ring electrode and the shell with a scavenging effect on these two spark surfaces.

Another feature of my invention is the fact that the central electrode is relatively large in diameter, providing greatest possible spark surface and lessened chance of variations in spark gap dimensions resulting from spark erosion.

Other advantages will appear from the following description.

In the drawing:

Fig. 1 is a vertical sectional view of a spark plug embodying my invention.

Fig. 2 is a bottom view of the same.

Fig. 3 is a bottom view of a modified form of construction.

In that embodiment of my invention shown in Figs. 1 and 2, 10 indicates a steel shell which is threaded at 11 to adapt the same to be screwed into the water jacketed cylinder head 12 of an internal combustion engine with the end of the plug substantially in the plane of the cylinder head. Within the shell 10 there is positioned a

heat-resisting porcelain core 13 carrying a central electrode 14 which is provided at the bottom with an imperforate dished disc 15, held by the end 14', and is provided with a shoulder 16 adapted to abut against a shoulder 17 in a central bore 18 in the core 13, said bore being enlarged at the bottom as indicated at 19. Said electrode 14—15 is adapted to be held in place by means of a nut 20 threaded onto the upper end of the electrode. A nut 21 is threaded onto the upper end of the electrode 14 to form a binding post in the usual manner. A clamp nut 22 fits over the upper part of the core 13 and is screwed into the top of the shell 10 as indicated at 23, a copper gasket 24 being positioned between the lower end of said nut and a shoulder 25 on the core 13. Another gasket 26, preferably made of nichrome, is positioned between a shoulder 27 on the lower part of the core 13 and a shoulder 28 formed in the shell 10.

On the lower end of the electrode 14 is a smaller porcelain core 29 which is non-reciprocably held thereon between the disc 15 of the electrode 14 engaging the lower end of the core 29 and the lower end of the core 13. The core 29 carries an intermediate electrode 30 in the form of a cupped ring which practically encloses the core. The outer end of the ring 30 is flanged outwardly, the periphery thereof being spaced a suitable distance from the inner wall of the shell 10.

Due to the intense heat generated when a spark plug of this character is used, I find it desirable to use a special metal for the intermediate electrode 30, such as the alloy known as nichrome or Marmet, which is non-expanding and has excellent heat-resisting qualities. The central electrode 15 may also be made of nichrome or other heat resisting alloy. "Marmet" is the trade name of a heat resisting alloy made by Wilbur B. Driver Company, Newark, New Jersey, by a secret process.

As shown in Figs. 1 and 2 the electrode disc 15, the intermediate electrode 30 and the shell 10 are concentric, and, therefore, the annular space 31 between the disc 15 and ring 30 is of uniform width, and the space 32 between the ring 30 and shell 10 is likewise of uniform width.

In the modification shown in Fig. 3, the intermediate electrode 30' is shown as slightly eccentric to the disc 15 and shell 10, so that the space 32' between the electrode 30' and shell 10 is not uniform, and the space between said electrode 30' and the disc 15 is not uniform. The result of this arrangement is that the spark will jump

the shortest gaps located at opposite points, between the disc 15 and electrode 30', and between the electrode 30' and the shell 10. This arrangement is not essential to the successful operation 5 of my spark plug, but is of value in providing two spaced apart sparks.

In some prior art structures, intermediate electrodes have been arranged for automatic reciprocatory movement on the central electrode, for the 10 alleged purpose of preventing carbon deposits, but this construction is open to the objection that the movable electrode does not always resume its intended position relatively to the fixed electrode and the sparking relationship of the 15 electrodes is thus impaired. Another objection is that such plugs cannot be used in radial engines, wherein some of the plugs are necessarily in inverted or non-vertical positions. Therefore, I avoid these objections by mounting my electrode 20 30 non-reciprocatorily but non-rigidly on the electrode stem 14. The electrodes are kept free from carbon by the scavenging effect of the combustion which occurs in the baffled gas chamber 25 of the plug and by the fact that my electrodes 15 and 30 are preferably made of nichrome or other suitable heat-resisting metals.

Changes may be made in details of construction without departing from the scope of my invention and I do not intend to be limited to the exact 30 form shown and described, except as set forth in the appended claims.

I claim:—

1. A spark plug comprising a shell which functions as an electrode, an insulating core in the 35 shell, a central electrode mounted in the core, a second insulating core mounted on the central electrode, an intermediate electrode surrounding said last mentioned core and having its lower peripheral edge substantially in the same plane 40 with the lower end of the central electrode and the lower end of the shell.

2. A spark plug comprising a shell which functions as an electrode, an insulating core in the shell, a central electrode mounted in the core, 45 a second insulating core mounted on the central electrode, an intermediate electrode surrounding said last mentioned core and having its lower peripheral edge substantially in the same plane with the lower end of the central electrode and the lower end of the shell, the intermediate electrode 50 being concentric with the central electrode and shell.

3. A spark plug comprising a shell which functions as an electrode, an insulating core in the shell, a central electrode mounted in the core, 55 a second insulating core mounted on the central electrode, an intermediate electrode surrounding said last mentioned core and having its lower peripheral edge substantially in the same plane with the lower end of the central electrode and the lower end of the shell, the intermediate electrode being eccentric to the central electrode and shell.

4. A spark plug comprising a shell which functions as an electrode, an insulating core in the shell, a central electrode mounted in the core, 60 a second insulating core non-reciprocably but non-rigidly mounted on the central electrode, an intermediate electrode surrounding said last

mentioned core and having its lower peripheral edge substantially in the same plane with the lower end of the central electrode and the lower end of the shell.

5. A spark plug comprising a shell which functions as an electrode, an insulating core in the shell, a central electrode mounted in the core and provided with a relatively large disc at one end, a second insulating core mounted on the central electrode, and an intermediate electrode 10 surrounding said last mentioned core, said intermediate electrode having a tubular body slightly flaring at its lower end.

6. A spark plug comprising a shell which functions as an electrode, an insulating core in the 15 shell, a central electrode mounted in the core and provided with a relatively large disc at one end, a second insulating core mounted on the central electrode, and an intermediate electrode 20 surrounding said last mentioned core, said intermediate electrode and insulating cores forming with the shell an annular, baffled gas chamber within the lower portion of the shell, said chamber being of greater cross sectional area intermediate its ends than at its exit end, and gradually diminishing in cross sectional area towards 25 said exit end.

7. A spark plug comprising a shell which functions as an electrode, an insulating core in the shell, a central electrode mounted in the core 30 and provided with a relatively large disc at one end, a second insulating core mounted on the central electrode, and an intermediate electrode surrounding said last mentioned core, said intermediate electrode and insulating cores forming 35 with the shell an annular, baffled gas chamber within the lower portion of the shell, said chamber being of greatest cross sectional area adjacent the proximate portions of the insulating cores and gradually diminishing in cross sectional area near 40 its exit end.

8. A spark plug comprising a shell which functions as an electrode, an insulating core in the shell, a central electrode mounted in the core, a second insulating core non-reciprocably but 45 non-rigidly mounted on the central electrode, and an intermediate electrode surrounding said last mentioned core, said second insulating core being of minimum diameter at the end abutting the first mentioned insulating core.

9. A spark plug comprising a shell which functions as an electrode, an insulating core in the shell, a central electrode mounted in the core and provided with a relatively large disc at one end, a second insulating core mounted on the 55 central electrode, and an intermediate electrode surrounding said last mentioned core, said intermediate electrode and insulating cores forming with the shell an annular, baffled gas chamber within the lower portion of the shell, said chamber being of greater cross sectional area intermediate its ends than at its exit end and gradually diminishing in cross sectional area towards 60 said exit end, the lower peripheral edge of the intermediate electrode being in substantially the same plane as the lower end of the central electrode and the lower end of the shell.

ARCH E. HORNBACK.
